VENTILATED AWNING

Merrill P. Kurtz, Akron, Ohio

Application January 15, 1947, Serial No. 722,095

5 Claims. (Cl. 20—57.5)

1

This invention relates to a ventilated awning which is preferably of metal construction. It comprises areas of roof surface with drains and ventilating channels between them. The drains and ventilating channels are not separate from the roof surface but are unitary portions of the elements which form the roof surface.

In a preferred form of the invention one edge of each metal element which forms the awning is shaped to form a trough, a portion of which serves as the drain and another portion of which comprises the bottom of the ventilating channel. If preferred, alternate elements may be formed with troughs along each edge, in which case the element between them will comprise no drain portion. Adjacent elements overlap, and the overlapping portion completes the ventilating channel. The ventilating channel permits air from the bottom of the awning to pass through to its upper side so that in summertime there will be no opportunity for a pocket of hot air to collect under the awning. Also, the ventilation of the awning lessens the danger of the awning being damaged in a high wind.

The awning will be further described in connection with the accompanying drawings, it being understood that the invention does not relate to end closures for the awning which will ordinarily be generally triangular in shape and cover the open triangular spaces at the ends of the awning. These ends may be formed of a single piece of metal or a plurality of pieces, as desired. They may be ventilated, but that is optional.

In the drawings:

Fig. 1 is a view in perspective of an awning which may be made of any width by decreasing or increasing to any desired number the five awning elements shown.

Fig. 2 is a section on the line 2—2 of Fig. 1;

Fig. 3 is a section of a modified construction;

Fig. 4 is a section through a further modification;

Fig. 5 is an enlarged detail in section showing one form of ventilating channel;

Fig. 6 is an exploded view of an alternative form of ventilating channel;

Fig. 7 is a front view showing one form of bottom edge formed by fabricating the lower ends of the several elements as shown in Fig. 8; and

Fig. 9 is a front view showing an alternative arrangement of the bottom edge which is formed of elements fabricated as shown in Fig. 10.

The ventilated awning of this invention is formed of a plurality of elements, preferably sheet aluminum, each of which comprises a roof por-

2

tion and a trough portion along one edge of the roof portion, as explained. The elements may be colored in any desired manner. Fig. 1 shows an awning made up of several such elements 5. Each element comprises the roof portion 6, one edge portion 7, a drain wall 8, a trough portion 9, and an upstanding flange 10 which forms a wall of the ventilating channel which will be described below. This element 5 is formed from a flat sheet 10 of aluminum by breaking in the usual manner. The bottom end 13 of the element 5 is bent over, preferably at an angle somewhat less than 90°, and its bottom edge may be shaped as desired.

The upper end of each edge portion 7 and drain wall 8 is preferably notched as at 15 to accommodate the flashing 16. This flashing 16 is fastened with its back flush against the wall of the building over the window or door which is to be protected. The elements 5 are riveted at 17 to the bottom flange 18 of the flashing.

The elements 5 are, likewise, riveted through the bottom of the drain at 20 to the parallel cross supports 22 and 23. The bottom portion of the awning is supported from the wall by the brace 25. There may be supports parallel with the elements at each edge of the awning braced by the support 25 and fastened to the flashing 16, but such elements are not essential. The method of supporting the elements and fastening them 30 to the wall is not an essential feature of this invention.

As shown in Fig. 2, the left-hand element 5 has a downwardly depending flange 7 which runs along one edge of the awning. The element at 35 the other edge of the awning will ordinarily have a like flange at the outside edge of the awning with no drain attached thereto (as shown in Fig. 1). Alternatively, there may be a drain at each 40 of the outside edges which is a unitary part of the outside elements, such as the drain composed of the portions 8, 9, and 10 of the element 5. Thus, the number of roof portions in the awning is equal to the number of elements used in its construction, the number of ventilating channels is one less than said number, and the number of drains is either one more or one less than said 45 number.

In the preferred awning each of the elements 5 (except the edge elements) comprises the downwardly depending flange 7 along one edge and a trough along the other edge. The downwardly depending flange 7 of one element overlaps the upwardly extending flange 10 of the adjacent element to form a ventilating channel. The downwardly depending flange 7 preferably rests against 50

the drain bottom 9 to prevent water from passing from the open drain to the covered ventilating channel although this is not essential. The upwardly extending flange 10 may meet the roof section 6 (see modified construction in Fig. 4) although for the purposes of ventilation it will usually be advisable to leave some space between the upper edge of the flange 10 and the under surface of the roof portion 6 as shown in Fig. 2.

Adjoining elements are bolted together by the bolts 30 which are provided with spacers 31, the width of the desired ventilating channel. These spacers separate the downwardly depending flange 7 of each element from the upwardly extending flange 10 of the adjacent element. The number of bolts and spacers 31 joining each of the elements will depend upon the length of the element and the manner in which the awning is assembled and supported from the wall. Other means may be employed for joining and spacing elements to form the ventilating channels.

Thus, an awning of any desired width may be assembled by uniting any desired number of the elements 5 in the manner illustrated in Fig. 2 with provision of a suitable element at each edge of the awning.

Fig. 3 shows an alternative arrangement in which the alternate roof elements are of a different construction. Thus, the elements 40 have no drain portions; whereas the alternate elements 41 comprise drain portions 42 on each side of the roof portion. The spacers 44 shown in Fig. 3 are wider than the spacers 31 of Fig. 2 and thus illustrate that a ventilating channel of any desired width may be provided.

Fig. 4 shows how a different effect is produced by using wider drain portions 50 with roof portions 51 of the same width as in Figs. 2 and 3. The roof portions may be colored differently from the drain portions, or alternate elements may be colored different colors, and a different over-all effect will be obtained by using drain portions and roof portions of different widths. Thus, if in the arrangement shown in Fig. 2 the roof portions are white and the drain portions are red, the over-all effect is a white awning with narrow red stripes. With the arrangement shown in Fig. 3, the elements 40 may be black and the elements 41 white. This will give an effect of white bands alternating with narrower black bands. If, on the other hand, the elements 40 are white and the elements 41 are black, the reverse effect is produced. Thus, it may at times be desirable to vary the width of the drain and produce a wider drain 50 as shown in Fig. 4 even though a drain of the width shown in Fig. 2 will be entirely satisfactory for drainage purposes. If the portions 50 of the drain shown in Fig. 4 are red and the roof portions 51 are white, the effect will be quite different from that obtained by coloring the roof portions 6 of Fig. 2 white and the drain portions red. Any desired coloring and spacing arrangements may be employed.

In Fig. 2 the drain portions are shown riveted to the cross supports. Whatever riveting arrangement is employed, a watertight construction is required. Instead of riveting the drain portions to the cross supports, the roof portions may be thus riveted, and spacers may be used if desired. However, riveting as shown in Fig. 2 will ordinarily be entirely satisfactory. With the alternative construction shown in Fig. 3, the only riveting required is riveting of the drain portions 42 to the cross supports. There is no reason for riveting the elements 40 to the cross supports.

Any suitable means for holding and mounting the elements may be employed. They must be so secure that a high wind will not damage them. Adequate ventilation protects against such damage.

The bottom edges of the several elements are preferably bent downward at 13. Two general constructions are possible, and these are illustrated in Figs. 7 and 9. In Fig. 7 the roof elements 6 are joined by the drain portions 9. These drain portions stop where the end portions 13 of the elements 5 are bent downward. Fig. 8 shows how the end of each element is cut and bent to form this structure. The roof portion 6 is bent downward to form the depending portion 13. The drain wall 8 must be slit or notched so that it may be bent to form the portion 8a which joins the part 13 and the portion 8b which adjoins the roof portion 6. In this modification the drain bottom 9 and drain wall 10 are cut off even with the joint between the portions 8a and 8b.

In the alternative arrangement shown in Fig. 9 the drain portions 9 between the roof portions 6 extend downwardly between the end portions 13. This construction is obtained by not severing the drain portion 9b from the drain wall 8a. This is shown clearly in Fig. 10. Thus, different effects are produced by the alternative arrangements illustrated in Figs. 7 and 9.

Suitable openings are provided in the drain channel to permit relatively free passage of air from underneath the awning to the space above the awning. If the upwardly bent flange 10 (Fig. 2) does not meet the roof portion 6 of the adjacent element 1, the hot air which collects under the awning in the summertime may easily be vented by providing a single opening in the downwardly depending flange 7 near the flashing 16. If the awning structure is such that it may otherwise be damaged by a strong wind, several such openings should be provided to give adequate provision for the passage of the wind. If the top edge of the outer wall 60 of the ventilating channel meets the flat roof portion of an adjoining element, as illustrated in Figs. 4 and 5, one or more ventilating openings will be required. Fig. 5 shows such openings 63 spaced at intervals along the length of the element. The edge of the depending wall 61 may be flush with the bottom of the drain 50 to prevent snow, etc., from entering and filling the ventilating channel. In that event openings, such as the openings 62, will be provided in the wall 61 which do not extend to the bottom of the drain 50. The openings 63 in the upturned flange 60 may extend to the edge of the flange 60 but may be spaced somewhat from it as shown in Fig. 5. The openings 62 and 63 are staggered to prevent rain beating on the bottom of the drain from splashing through the openings to the under side of the awning. The bolt 64 passes through the flanges 60 and 61 and carries the spacer which separates them.

In an alternative arrangement the wall 60 does not extend up to the roof portion 51, and the wall 61 does not extend down to the bottom of the drain 50. In fact, it is not necessary that the flanges 60 and 61 overlap. If they do not overlap, other means than the bolts and spacers shown will be provided for holding them in the desired spaced relation.

An alternative ventilating arrangement is shown in Fig. 6. Here the two elements 70 and 71, of the same general construction as shown in Fig. 2, are exploded and the spacer 72 is shown between them. In the element 70 the ventilating

openings 73 are located right at the break. They will be a little less easily visible if located a short distance below the break. In the element 71 the ventilating openings 74 are provided by notching.

Modifications of the specific structures shown are permissible within the scope of the appended claims which define the invention.

What I claim is:

1. A ventilated awning which includes a sheet metal element comprising a drain portion and an upturned flange at one edge of the drain portion, and overlapping said edge of this element another sheet metal element comprising a roof portion and at the edge of the overlapping portion a downturned flange, the upper edge of said upturned flange meeting the undersurface of said roof portion and the lower edge of said downturned flange meeting the upper surface of said drain portion, said flanges being spaced from one another, ventilating openings in each flange spaced from the bottom thereof, the openings in the respective flanges being staggered along their length.

2. A ventilated awning which includes a sheet metal element comprising a drain portion and an upturned flange at one edge of the drain portion, and overlapping said edge of this element another sheet metal element comprising a roof portion and at the edge of the overlapping portion a downturned flange, the upper edge of said upturned flange meeting the under surface of said roof portion and the lower edge of said downturned flange meeting the upper surface of said drain portion, said flanges being spaced from one another, ventilating openings in each flange spaced from the bottom thereof, the openings in the respective flanges being staggered along their length, the opposite edges of the respective elements overlapping sheet metal elements adjacent thereto and each forming with its next adjacent element the described arrangement of roof portion, drain portion and flanges with staggered ventilated openings.

3. A ventilated awning which includes a sheet metal element comprising a drain portion and an upturned flange at one edge of the drain portion, and overlapping said edge of this element another sheet metal element comprising a roof portion and at the edge of the overlapping portion a downturned flange, the upper edge of said upturned flange meeting the under surface of said roof portion, and the lower edge of said downturned flange meeting the upper surface of said drain portion, said flanges being spaced from one another, ventilating openings in each flange spaced from the bottom thereof, the openings in the respective flanges being staggered along their length, the opposite edge of said first-described sheet metal element being formed into an up-

turned flange with ventilating openings therein, the space between its flanges forming a roof portion with a drain portion on each side of it, the roof portion being in a plane above the drain portions.

4. A ventilated awning which includes a sheet metal element comprising a drain portion and an upturned flange at one edge of the drain portion, and overlapping said edge of this element another sheet metal element comprising a roof portion and at the edge of the overlapping portion a downturned flange, the upper edge of said upturned flange meeting the under surface of said roof portion and the lower edge of said downturned flange meeting the upper surface of said drain portion, said flanges being spaced from one another, ventilating openings in each flange spaced from the bottom thereof, the openings in the respective flanges being staggered along their length, said first-described sheet metal element including also a roof portion in a plane above the drain portion with its opposite edge formed into a downturned flange with ventilated openings therein.

5. A ventilated awning which includes a sheet metal element comprising a drain portion and an upturned flange at one edge of the drain portion, and overlapping said edge of this element another sheet metal element comprising a roof portion and at the edge of the overlapping portion a downturned flange, the upper edge of said upturned flange meeting the under surface of said roof portion, and the lower edge of said downturned flange meeting the upper surface of said drain portion, said flanges being spaced from one another, ventilating openings in each flange spaced from the bottom thereof, the openings in the respective flanges being staggered along their length, the opposite edge of said second-described sheet metal element being formed into a downturned flange with ventilating openings therein.
